UNITED STATES PATENT OFFICE.

WILLIAM E. MCPHERSON, OF RENSSELAER, NEW YORK.

BERTH-HAMMOCK.

No. 894,849.

Specification of Letters Patent.

Patented Aug. 4, 1908.

Application filed February 20, 1908. Serial No. 416,887.

To all whom it may concern:

Be it known that I, WILLIAM E. MCPHERSON, a citizen of the United States, residing at Rensselaer, in the county of Rensselaer 5 and State of New York, have invented certain new and useful Improvements in Berth-Hammocks, of which the following is a specification.

The present invention is in the nature of 10 an improved hammock of that type which is employed in the berths of railway cars and steamers to receive the apparel and personal belongings of the occupant.

The object of the invention is to design a 15 hammock of this character which is of simple and inexpensive construction and is so designed as to maintain the articles placed therein in a neat and tidy condition and prevent the usual wrinkling and mussing of the 20 same.

A further object of the invention is the 25 provision of a hammock which is of dust-proof construction and will prevent cinders and similar foreign matter from settling upon the clothes.

For a full description of the invention and the merits thereof and also to acquire a 30 knowledge of the details of construction and the means for effecting the result, reference is to be had to the following description and accompanying drawings, in which:

Figure 1 is a front elevation of a berth 35 hammock embodying the invention, showing the flap in an elevated position; Fig. 2 is a similar view showing the flap as closed, and Fig. 3 is a transverse sectional view through the pocket when open.

Corresponding and like parts are referred 40 to in the following description and indicated in all the views of the drawings by the same reference characters.

The device comprises a hammock or pocket 45 which may be formed of any tough and pliable material such as canvas and which is designed to be suspended from the walls or ceiling of the berth.

Referring to the drawing the numeral 1 50 designates the back of the hammock, the said back being formed with a straight upper edge and a curved lower edge. The front 2 of the hammock is approximately crescent-shaped, the lower edge thereof being curved in a manner corresponding to the lower edge of the back and being secured thereto by any 55 suitable means such as the stitching 3, while the upper edge is curved downwardly to

admit of ready access being had to the interior of the hammock.

Interposed between the back 1 and front 2 is an intermediate partition 4 which is also 60 approximately crescent-shaped and divides the hammock into two separate compartments. It will be observed however that the upper edge of the intermediate partition 4 extends upwardly beyond the front 2 so 65 that the occupant of the berth can readily grasp the same and swing it to either side so as to obtain access to either of the compartments of the hammock. The flap 5 may either be integral with the back 1 or secured 70 thereto and is designed to overlap the front 2 so as to exclude dust and cinders from the interior of the hammock. For the purpose of holding the flap 5 in normal position a strap 6 is utilized, one end of the strap 75 projecting beyond the edge of the flap and being formed with a button-hole designed to detachably engage a button 7 upon the front 2.

For the purpose of suspending the hammock or pocket in position a loop 8 is provided 80 at each end thereof, the said loops being shown in the present instance as formed by doubling strips upon themselves and securing the ends thereof to the hammock.

For the purpose of protecting the edges of the various members of the hammock the same are shown as provided with a binding 9 which may be of leather or other suitable material. In this connection it may be 90 called to attention that the binding strip 9^a extending around the lower edge of the hammock is held in position by means of the same line of stitching which extends through the front, back and intermediate partition of 95 the hammock and holds the said members securely together. In the application of the device the hammock is designed to be suspended from the walls or ceiling of the berth by means of the loops 8, the lighter articles 100 being placed upon one side of the intermediate partition 4 while the heavier articles are placed upon the opposite side of the partition and thereby separated from the lighter articles. The flap 5 when secured in position by means of the strap 6 retains the articles within the hammock and excludes dust and cinders from the same.

It may be mentioned that my improved 105 berth hammock can be hung up in the same manner as the ordinary berth hammock commonly in use at the present time.

Having thus described the invention, what is claimed as new is:

A berth hammock comprising a back formed with a straight upper edge and a curved lower edge, a crescent-shaped front applied to the back, the lower edge of the front being secured to the lower edge of the back and extending upwardly to the upper edge of the back while the upper edge of the front is disposed below the upper edge of the back, a crescent-shaped partition interposed between the front and back and having the

upper edge thereof disposed between the upper edges of the front and back, a flap carried by the back for closing the pockets, and a suspending loop at each end of the hammock.

In testimony whereof I affix my signature in presence of two witnesses.

WILLIAM E. MCPHERSON.
